UNITED STATES PATENT OFFICE.

ISABELLE WURDACK AND ARTHUR WURDACK, OF NORMANDY, MISSOURI.

DESIGN FOR A CHAIR.

Application filed December 29, 1922. Serial No. 4,742. Term of patent 14 years.

To all whom it may concern:

Be it known that we, ISABELLE WURDACK and ARTHUR WURDACK, citizens of the United States of America, residing at Normandy, Saint Louis County, in the State of Missouri, have invented a new, original, and ornamental Design for a Chair, of which the following is a specification, reference being had to the accompanying drawing, forming part thereof.

We claim:

The ornamental design for a chair, as shown.

ISABELLE WURDACK.
ARTHUR WURDACK.
